UNITED STATES PATENT OFFICE.

OLIVER O. APP, OF NEW YORK, N. Y.

TUNNELING OR EXCAVATING MACHINE

1,219,419.

Specification of Letters Patent. Patented Mar. 20, 1917.

Application filed September 10, 1910. Serial No. 581,330.

To all whom it may concern:

Be it known that I, OLIVER O. APP, a citizen of the United States, residing at the city of New York, in the borough of Manhattan and State of New York, have invented certain new and useful Improvements in Tunneling or Excavating Machines, of which the following is a full, clear, and exact description.

This invention relates to tunneling machines and has for its object the provision of apparatus for driving tunnels or sinking shafts with a maximum of efficiency and with a minimum expenditure of power and wear on the tools. I have devised a mechanism in which, if so desired, all of the tools employed may be driven at substantially the same rate of cutting speed and in which each of the respective tools is subjected to substantially the same amount of wear. Furthermore, the parts are so arranged that certain of the tools may be broken or otherwise unfitted to perform their function without materially impairing the action of the apparatus; indeed by reason of the novel arrangement of parts hereinafter set forth, it is possible to cut a tunnel with but a single tool, such tool being adapted to be passed successively over every portion of a given area. Other objects of my invention will be hereinafter set forth and more particularly pointed out in the appended claims.

In the drawings which form a part hereof:

Figure 1 is a vertical axial section taken through one form of my tunneling apparatus;

Fig. 2 is a transverse section taken on line II—II of Fig. 1;

Fig. 3 is a similar section taken on the line III—III of Fig. 1;

Fig. 4 is a transverse section taken on line IV—IV of Fig. 1, a portion of the equalizer therein shown being broken away in order to show the air channels therein; the heads in this instance being both equipped with fluid pressure operated tools;

Fig. 5 shows a modified form of my tunneling apparatus; being a section of such apparatus corresponding to that shown in Fig. 1;

Fig. 6 shows a modified form of mechanism for supporting the planetary driven tunneling heads; this particular embodiment of my invention illustrating means for

regulating or adjusting the distance between the centers of such heads;

Fig. 7 is a fragmentary side elevation of the mechanism illustrated in Fig. 6;

Fig. 8 is another modification illustrating different means for accomplishing the separation of the planetary driven heads; and

Fig. 9 is an end elevation of an apparatus embodying the principles of my invention; showing the application of a muck-shield to the cutting or tunneling heads;

Figs. 10 and 11 are details showing the valve-chest in section.

Referring now to the form of device illustrated in Fig. 1, we will consider the respective features of the mechanism therein shown in sequence.

Planetary drive.

The means by which I accomplish the movement of the tools, hereinbefore referred to, essentially comprises a plurality of rotatable heads which are so mounted that in addition to their individual rotation about their respective axes, they may further be revolved about a common axis, which may be that of the general mechanism. In the particular embodiment of my invention herein shown, a hollow main shaft 1 carries thereon a gear 2 which is positioned for engagement with a pinion 3, which is driven by a suitable motor 4. The gear 2 is keyed or otherwise secured to the shaft and is movable longitudinally with respect to the axis of the pinion 3, the face of such pinion being of sufficient width to permit of considerable movement of the gear thereover, while being maintained in engagement therewith. The motor 4 is suitably housed in a casing 5, a portion of which casing is secured to, and in this instance forms, an integral part of a cylinder 6. This cylinder is disposed around and is preferably concentric with, the shaft 1, and has therein a piston 7 which is fixedly secured to a second hollow shaft 8, this shaft being disposed around the first and virtually forming a sleeve therefor. The forward end of the cylinder is closed by a head 9 from the front face of which projects a cylindrical extension 10 which constitutes a stuffing box for the hollow shaft 8; a suitable gland 11 being provided at the forward extremity of this box. The rear end of the cylinder 6 is correspondingly closed by a

65

75

80

85

90

95

100

105

head 13, a downwardly extending portion of which may be secured in any suitable manner to the casing 5. This head is also provided with a stuffing box, the gland of which has been designated 14. The hollow shaft 8 is adapted to be reciprocated by the piston 7 and may be also adapted for rotation. The forward end of this shaft carries a gear 15 which is secured thereto in any suitable manner. This extremity of the shaft 8 also has revolvably mounted thereon directly to the rear of gear 15, one side or section of a bracket or tunneling head support 16. This support preferably consists of two principal sections, one of which is mounted upon the extremity of the shaft 8 in the manner above described, and the other of which is keyed to the forward extremity of the shaft 1. The gear 15 and a collar 17 on shaft 8 prevent longitudinal displacement of the support. The respective sections of the support or bracket are secured together by the connecting parts 18 and the sections have journaled in preferably diametrically opposite portions thereof the hollow spindles 19, each of which carries a pinion 20 which is disposed for engagement with the gear 15. It will be observed that the face of the gear 15 is relatively somewhat wider than the faces of the pinions 20, so as to permit of lateral displacement of said pinions with respect to said gears, for reasons hereinafter set forth. The shaft 8 is prevented from forward endwise movement with respect to shaft 1 by a collar 21, while the rear end of the shaft 8 correspondingly bears against the hub of the gear 2. As the forward section of the head support 16 is keyed to the shaft 1, when the latter is rotated by the gear 2, the support will be correspondingly rotated, and as the gear 15 may be held stationary, or comparatively so, the pinions 20, by reason of their engagement therewith, rotate the spindles 19 and thereby the tool-carrying tunneling heads 22, which are carried upon the forward extremities of these spindles, and hence may properly be said to be planetary driven.

It is obvious, of course, that the relative speeds of rotation of the heads with respect to the driving shaft 1, may be varied by variously rotating, or permitting the rotation of, the shaft 8. If this shaft be permitted to freely revolve at the same speed as that of shaft 1, the heads would cease to turn individually; but would still continue to rotate around the axis of shaft 1; while if the rotation of shaft 8 be retarded, the rotation of the heads 22 about their own axes will be correspondingly accelerated. In other words the speed and direction of rotation of the respective shafts determines the relative direction of rotation and speeds of the heads and support.

65 The particular arrangement of mechanism

employed in this embodiment of my invention for obtaining these differential speeds will be hereinafter described.

Supporting devices.

70

I shall next consider the centering or supporting devices whereby the tools are properly positioned in the shafts and held to their work. The cylindrical extension 10 is journaled in a hollow block or annulus 30 75 which is shown in cross section in Fig. 3. This block is provided on opposite sides thereof with trunnions 31, which in turn are journaled at 32 in the octagonal frame 33. This frame in turn carries a pair of trunnions 34 which are disposed substantially at right angles to those first mentioned, and an outer or supporting frame 35 is mounted upon these trunnions. This construction virtually provides a universal joint, so that 80 the axis of the machine may be swung in any direction with respect to the frame 35, within certain limits. The outer frame carries a plurality of jacks 36, the construction of which will be hereinafter more particularly set forth.

The rear end of shaft 1 has somewhat correspondingly mounted thereon a block or frame 37; suitable ball-bearings 38 being provided to permit free rotation of the driving shaft within its supporting block, the balls being held in position by rings 39; and the outer sides of these rings in turn bearing against the collars 40 and 41 which are secured to shaft 1 in any suitable manner. 95 Block 37 has been shown in end elevation and partial section in Fig. 2 and carries the rear jacks 42. These jacks are substantially like those above referred to, except that the adjustable parts are somewhat 100 longer, so that a description of one of the jacks will suffice for all. The block 37 is provided with a plurality of recesses 43 which receive caps 44; these caps being screwed firmly upon the ends of the hollow 105 studs 45. Each of these studs is threaded upon its outer face for a considerable distance for engagement with a nut 46; and each nut is provided with an annular groove or recess 47 which is adapted for engagement 110 with a pair of semicircular plates 48; these plates being secured to the frame 37 by screws 49, or in any other suitable manner. It is obvious that when a nut 46 is turned, its 115 corresponding stud 45 will be moved into or out of the frame 37, according to the direction of rotation of said nut. The outer extremities of the studs are flattened on opposite sides thereof to afford seats for the hubs of rollers 50; these rollers being mounted upon pins 51 which extend out laterally from the flattened portions of the studs. These rollers are tapered and rounded slightly so as to permit them to 120 conform to the sides of the tunnel and by 125

means of the nuts 46 the said rollers can be driven outwardly into engagement with the walls of the tunnel and thereby center the axis of the machine. In the interior of each 5 stud 45 is an hydraulic piston or plunger 51 which is keyed against rotation by the key 52 which rides in a slot 53. The outer extremity of each of these plungers carries a shoe 54 which is preferably made removable so that it may be replaced when worn. This 10 construction constitutes an inner and fluid-pressure operated jack; any suitable fluid being admitted behind the piston through the orifice 55. The fluid pressure system will be later described, but it is obvious that when 15 fluid is introduced under pressure back of the plungers 51, the same will be driven outwardly, firmly engaging the walls of the tunnel and locking the particular frame to 20 which they are attached in position. In operation, assuming that the forward plungers are under pressure and that the universally jointed frame 35 is thereby firmly positioned; pressure may be applied to the 25 rear face of piston 7 which will urge the shaft 8, and thereby the support 16 and heads 22, forwardly; the shaft 1 also being pulled forwardly by reason of the engagement of the forward extremity of shaft 8 30 with collar 21. As the heads work their way into the rock or other material through which the tunnel is being driven, the frame 37 will be correspondingly pulled along by the shaft 1 and the rollers of the rear jacks 35 42 will guide this advance along the proper line.

It should be here observed that it is possible to change the direction of the cut by properly adjusting the nuts 46. For example, if the two upper spindles 45 of the frame 37 be thrown outwardly, and the lower spindles correspondingly inward, the axis of shaft 1 will be obliquely disposed with respect to the axis of that section of the 45 tunnel which has already been cut, so that the heads will thereafter cut into the rock obliquely. This constitutes a very important feature of my invention.

Assuming now that the piston 7 has traversed its stroke, the rear jack plungers will be driven into engagement with the tunnel walls and the forward plungers will be retracted, by respectively opening and closing the cocks hereinafter referred to which control the pressure-fluid which actuates said jacks, leaving of course the rollers of the forward jacks still in engagement with the tunnel walls, whereupon fluid pressure will be applied to the forward side of piston 7, and as the rear frame is held fast, the forward frame will be correspondingly advanced.

This construction permits of substantially continuous operation and it is not necessary to stop the tools at any time, since by reversing 65 the direction of travel of the piston

while correspondingly changing the sets of plungers which are in operative engagement with the tunnel walls, the tunnel may be driven forwardly without stopping the cuttings heads.

70

Tool-holding heads.

The heads 22 carry the tools 60 which may be of any suitable description, such, for example, as fluid pressure operated tools, electric or spring tools, aero-electric tools, or they may even be non-revolving straight steel bars, which constitute cutting tools. Furthermore it is obvious that the tools in the respective heads may be different in character. Thus, for example, I may have pneumatically-operated tools, such as chisels, carried on one head, and steel cutting bars carried by the other head, as shown in Fig. 5. This arrangement is of particular utility 85 in driving through certain formations, *i.e.*, shale or schist; the shale being dislodged in flakes by the action of the chipping tool and such flakes being then broken or ground up by the action of the cutting tools carried by the other head. The particular embodiment of my invention herein shown carries but two heads, but it is within the scope of my invention to have either a single head or any desired number.

85

Equalizing device.

Referring again to Fig. 1, the spindles 19 have collars 61 secured to their forward ends, to the rear of the cutting heads; these 100 collars being so mounted on the spindles as to permit rotation of the spindles therein, suitable fixed collars 62 and 63 being positioned upon either side of each loosely mounted collar 61. The construction of the 105 collars 61 is best shown in Fig. 4, said collars being interiorly grooved as at 64 and each of the spindles being provided with one or more ducts 65 which afford communication between the interior of the hollow spindles and grooves 64. The collars 61 are provided with trunnions 66 which are journaled in the respective extremities of the equalizer bars 67; these bars in turn being pivoted upon trunnions 68 which are positioned upon 110 the respective sides of a block 69 which is securely carried upon the forward extremity of the shaft 1. Oppositely disposed ducts 70 extend outwardly through the sides of block 69 and through the trunnions thereof, a little to one side of the axis of such trunnions, and communicate with corresponding ducts 71 which extend through the length of the equalizer bars 67; and each of the collars 61 is correspondingly provided with 115 ducts or conduits 72, so that communication is afforded through the respective grooves and ducts with the interior of shaft 1. Air or other suitable fluid is thus delivered under pressure to the interior of the spindles 120 125 130

19 through the hollow shaft 1, and is thence conducted through the small pipes 73 to fluid pressure operated tools. The supporting structure for the heads above described 5 permits the parts to nicely adjust themselves to the varying conditions of the work.

Normally, of course, the equalizing device provides means for equalizing the strain upon the tools, since when, for example, at 10 a given instant more or less rock is encountered in the upper half of the bore and muck in the lower half thereof, the equalizing device permits the heads and consequently the tools to adjust themselves to the 15 conditions and equalize the strain thereupon.

When the condition of the work renders the equalizing action undesirable, the spindles 19 may be locked against longitudinal movement by means of the collars 74 which 20 may be slipped over their respective spindles 19 into engagement with the support 16, and locked in such position on said spindles.

The collars 74 serve a further function in that by shifting their positions along the respective spindles while maintaining both collars in contact with the inner face of the support 16, it becomes possible to dispose one of the heads in a forward or cutting position while the other is correspondingly retracted. Thus if one head be provided with chipping tools while the other is equipped with cutting tools, either or both sets of tools may be used as found necessary.

The heads may be mounted upon the extremities of the spindles 19 by being screwed thereupon or in any other suitable manner and the rear extremities of each of these spindles carries a cap 75 which closes the end thereof.

40 Regulating mechanism.

The regulating mechanism used in the embodiment of my invention shown in Fig. 1, comprises a band-brake 80 and a coöperating pulley 81 therefor, provides means for regulating the travel or slippage of the shaft 8. This pulley may be integral with the rear extremity of said shaft and is grooved upon its periphery for the reception of the brake-band. This brake is in some respects of the usual construction, being provided with a tightening member 82 (shown in Fig. 2) which is secured to a rock-shaft 83 which is mounted in a lug 84, said lug extending out laterally from the block or frame 37. The rear extremity of the rock shaft carries an operating lever 85, preferably clamped thereto, so as to permit of relative adjustment therebetween. The 60 middle of this lever, which preferably extends some distance beyond the axis of the machine, bears against a cam 86 carried on shaft 1; so that the rock shaft will be oscillated one or more times, according to the

formation of the cam, during each revolution of shaft 1.

Assuming now that but a single depression 87 has been formed in the cam surface, it is evident that the outer cam surface, when in engagement with the lever, will 70 normally tend to taunt the band-brake and lock the shaft 8 against rotation; but when the lever encounters the depression 87, the tension of the band-brake will be relieved. The gear 15 will then be no longer able to 75 drive the pinions 20 at the speed at which they had previously been driven and will in turn, under the action of the said pinions, be rotated more or less rapidly, according to the brake pressure exerted, in the same 80 direction as that in which shaft 1 is being driven. As the depression in the cam thereafter passes from under the lever, the brake will be again immediately applied, so that the slippage of shaft 8 will have been but 85 momentary and the length of the recess or depression in the cam will determine the period of said slippage, while the depth of the recess will correspondingly determine 90 the rate thereof. The shape of this cam 95 hence affords means for regulating the relative speed of the heads and also effects the displacement of the tools carried thereby from the paths in which they would otherwise have continually traveled. This arrangement therefore affords means for causing each tool to traverse every point upon the surface to be cut, so that all of the tools are bound to wear equally.

In addition to being automatically controlled the band-brake may be controlled manually by the operator by means of the lever 85 by properly adjusting it with respect to the rock shaft. This same adjustment obviously also affords means for determining the brake pressure to be exerted upon pulley 81.

Fluid-pressure controlling appliances.

Referring now more particularly to Figs. 10 and 11, upon the upper portion of the cylinder 6 is seated a chest 95 in which are positioned the valves for controlling the respective plungers 51 and the piston 7. Five small handles 96 are positioned on each side 115 of this chest, four of such handles serving to control the respective plungers upon the forward frame, while four upon the other side of the chest correspondingly control the plungers carried by the rear frame; the remaining handle upon each side serving, respectively, to control the admission of fluid to one or the other sides of piston 7. A suitable pump 97 is provided for delivering the fluid pressure through the respective pipes to the several jacks, this pump being driven by a motor 98. The pipes 99 which extend rearwardly from the chest toward

the frame 37, may be flexible to allow for the approach of said frame toward the front of the machine or other suitable arrangements may be provided, such as flexibly connected pipe sections or the like.

Muck-conveyer.

Any suitable muck-conveyer may be provided in connection with the apparatus and in this embodiment of my invention I have shown a drag conveyer 100 which is provided with a series of buckets or like devices, the conveyer passing successively around the head pulley 101, the rear pulley 102 and idler 103. The rear pulley is driven by means of a suitable sprocket secured to the same shaft as the pulley which is driven by the chain 104; said chain being in turn driven from the sprocket 105 which is carried by the shaft 106; this shaft being driven by the worm-wheel 107 and worm 108. A suitable motor 109 may be provided for driving this worm.

Water connections.

It is desirable to supply water under pressure, delivering the same against the face of the work and hence a water pipe 110 is disposed along the axis of shaft 1, the forward extremity of this pipe being screwed firmly into engagement with the center of the block 69, as shown in the similar arrangement illustrated in Fig. 5, channels being provided through this block adjacent to ducts 70, substantially parallel thereto, but directly along the axis of the trunnions 68. The extremity of each of these trunnions has screwed thereon a suitable connection 111 whereby water may be delivered to the per-

forated spray pipes 112 in the manner shown in Fig. 4. As the pipe 110 is rotated by reason of its engagement with the block 69, it is necessary to provide a suitable slip-joint whereby said pipe may be connected to the stationary water supply pipe 113. Correspondingly the extremity of shaft 1 is joined to a stationary pipe 114 by a slip-joint which may be of any suitable construction such as that indicated in Fig. 1, joints of this character being quite common.

Modification illustrated in Fig. 5.

In the modification shown in Fig. 5, the main shaft 120 is directly driven by a motor 121 through the instrumentality of a worm 122 and worm-wheel 123; worm-wheel 123 being feathered upon the shaft 120 so as to permit longitudinal movement of the said shaft therethrough. The motor is carried upon a suitable platform 124 which is supported at its rear end by the bracket 125, which is journaled around the shaft 1, and by the forward bracket 126 which is secured to the cylinder 127. This cylinder is dis-

posed concentrically about the axis of shaft 120 and carries a piston 128, which in this form of device is preferably provided with piston rings 129 or the like; the piston 128 being secured directly to the shaft 120. The cylinder 127 is supported by trunnions (not shown) which are journaled in the frame 128; this frame in turn being pivotally connected to the outer frame 129 by trunnions 130. The trunnions for supporting the cylinder 127 are similar in construction to the trunnions 31 utilized to support the annulus or hollow block 30, as shown in Fig. 3. This method of connecting the cylinder to the outer or jack-frame provides a substantially similar universal joint construction to that utilized in the form of device shown in Fig. 1. The heads 131 and 132 are mounted in similar fashion to those shown in said Fig. 1 and are correspondingly driven. In this modification I have shown the heads as equipped respectively with different styles or types of tools, the tools shown in connection with head 131 being pneumatic chipping tools 133, while the head 132 is provided with fixed cutting bars 134. It may be noted in connection with the latter form of tools that this mechanism is adapted to be continuously operated without necessitating any stoppage thereof for the purpose of sharpening tools of this description, since it is obvious that as the cutting tool is rotated about the axis of the supporting spindle, the forward edge thereof will gradually be worn round until the tool becomes too dull to effectually abrade the surface of the rock or other material against which it is being operated; but by merely reversing the motor, the heads will be correspondingly rotated in reverse direction which will cause the opposite face of each of these tools to be brought into action and the tool will then be self-sharpening. In its general action the modification illustrated in Fig. 5 is very similar to that hereinbefore described, the principal differences being the method of driving the main shaft, and the manner of mounting the cylinder directly within the universal joint frames; and it will be noted that in this case the gear 135 which corresponds to the gear 15 in the former device is, in this instance, held stationary at all times by reason of its being secured directly to the cylindrical extension 136 which forms a part of the forward head of the cylinder. When the shaft 120 is driven forwardly, the spindles 137, which herein are somewhat longer than those above mentioned, are urged downwardly through the support 138, the pinions 139 slipping thereover. These pinions, however, are feathered to the said spindles so that the latter will rotate no matter in what position the heads may be.

Extensible head mechanism.

In Figs. 6 and 7 I have illustrated means by which the tool-carrying heads 140 may be swung outwardly from the axis of the machine, thus enabling a tunnel of much greater diameter to be driven than would be possible with the same size of head were they supported in the manner above described. The heads 140 are mounted upon spindles 141 which are journaled in the respective outer extremities of the arms 142, the inner extremities of said arms being correspondingly pivoted to spindles 143. These latter spindles are carried upon a cross-head 144 which is in turn revolvably mounted on the extremity of the main shaft, in this case numbered 145. The relative positions of the arms 142 is determined by the screws 146; the heads of these screws being revolvably held in sockets 147 which are pivoted upon either side of the hub of the cross-head. The pivoted nuts 148 are correspondingly mounted, adjacent the outer extremities of the arms 142 so that when a turning pin is inserted into the holes 149 provided in the extremity of each of the screws 146, the said screws may be rotated clockwise or counter-clockwise and cause the said bars to swing inwardly or outwardly as desired. The heads in this instance are again planetary driven, the gear 150, being a fixed, relatively fixed or intermittently movable gear; the pinions 151 which are carried upon the spindles 143, being disposed in engagement with said gear, and in turn driving the gears 152. These latter gears in turn intermesh with the intermediate gears 153 which drive the gears 154, these latter gear-wheels being secured to spindles 141 and thereby serving to rotate the heads. By reason of the respective trains of gears it is hence possible to continuously drive the heads, no matter in what position they may be disposed. This construction also permits one of the heads to be screwed inwardly until its periphery substantially contacts with the axis of the machine; while the other may be screwed outwardly to such an extent that its periphery will be disposed at a distance from the axis of the machine substantially equal to the diameter of the other head. The heads will thus be non-symmetrically disposed, but will nevertheless be adapted to efficiently cut a tunnel of large diameter.

Modification of extensible head mechanism.

In Fig. 8 I have illustrated another form of mechanism which is adapted to extend the heads in the manner above described. In this instance, however, the heads will in all cases be symmetrically disposed and the centers thereof will be at all times in alinement with each other and with the principal axis of the machine. The arrangement here em-

ployed embodies, in a way, a lazy-tongs construction. The heads 160 are carried upon spindles which extend through the outer extremities of the bars or links 161, of which latter four are provided in all; the inner extremities of these bars being connected to the cross-heads 162; and this cross-head is in turn pivotally carried upon the extremity of the main shaft 163. The pivotally mounted nuts 164 are carried upon the outer extremities of each of the arms of the respective cross-heads and right and left-hand threaded bolts 165 pass through the bodies of these nuts in the manner shown in Fig. 8. A single bolt has therein been shown, since one alone will suffice to accomplish the extension of the heads in the manner described. When the nuts 164 are screwed inwardly upon this bolt, the heads are correspondingly forced apart by reason of the toggle action of the links and cross-heads. In this form of construction an intermediate gear in the train may be omitted; the gears 165, 166, which drive the heads, being driven directly by the gears 167; the latter being driven by the pinions 168 which are always in engagement with the central or relatively stationary gear 169. The dotted lines in Fig. 8 indicate the position of the heads when outwardly extended and show the relative sizes of tunnels which would be cut by the heads when inwardly or outwardly positioned. By using this type of head it is possible to first drive a small tunnel of the diameter indicated by the solid line 170 and thereafter traverse the same tunnel with the heads in extended position to enlarge the diameter thereof to that indicated by the dotted lines 171.

Muck-shield.

Fig. 9 illustrates a device, which may be advantageously used in connection with the planetary driven heads, which consists of a shield 180 which is preferably disposed so that its front face is substantially flush with the front face of the tool-carrying heads 181 and 182, and these heads hence extend through apertures 183, 184, in the shield. The shield is carried by suitable arms 185 which extend laterally out from the equalizer block 186. This shield is provided for the purpose of retaining fragments of rock and soft muck which will be loosened by the tools in front of the heads; the accumulated debris being thereafter collected from below the shield in any suitable manner. Such a shield is of utility where a tunnel is being driven through relatively soft material and particularly adapts the tunneling apparatus for caisson work.

Résumé.

In general it may be stated that the planetary drive may be of any suitable descrip-

tion, and in the accompanying claims this term will be understood to include not alone planetary gear drives, but all equivalents thereof. The term "planetary drive" therefore is to be deemed sufficiently broad to cover any structure in which one or more heads may be driven rotatively about their own axes while being simultaneously rotated about another axis out of alinement with the first.

10 It is obvious that my mechanism is adapted to cut any shape of tunnel or shaft desired by stopping the rotation of the main head and rotating the cutting or tunneling heads, and by elevating or lowering the forward end of the machine; and it is obvious, further, that additional auxiliary heads may be provided, if desired.

15 In machines constructed in accordance with the principles of my invention the cutting speed of the tools may be made practically the same at the periphery of the tunnel as at the center, since the cutting heads should preferably revolve at a higher rate 25 of speed than the main head. This does away with the problem of dead centers and overcomes the necessity for too rapid travel of the cutting tools at the periphery of the cut.

20 30 The provision of the universal joint in connection with the forward traveling support, permits the direction of the tunnel to be changed while the machine is being operated; and the fluid pressure jacks may be 35 used to change the direction of the machine, whether the same be operating vertically, horizontally or obliquely.

Having described my invention, I claim:

1. In a tunneling and excavating machine, 40 a rotatable support, a rotatable tunneling head, and means for rotating one of said parts at a variable speed with reference to the other of said parts.

2. In a tunneling and excavating machine, 45 a rotatable support, a rotatable tunneling head, and automatic means for rotating one of said parts at a variable speed with reference to the other of said parts.

3. In a tunneling and excavating machine, 50 a revolute support, a revolute tool-carrying head carried by said support, the respective axes of the support and head being out of alinement, means for rotating said support, and driving means for revolving 55 said head about its pivotal axis, driven by said rotating means.

4. In a tunneling and excavating machine, 60 a revolute support, a revolute tunneling head carried thereby, means for driving one of said parts at a fixed speed and means for driving the other of said parts at a variable speed with reference to the other of said parts.

5. In a tunneling and excavating machine, 65 a rotatable support, a rotatable tunneling

head, and means for rotating the head at a variable speed with reference to the rotatable support.

6. In a tunneling and excavating machine, 70 a tunneling head, for driving mechanism for rotating the same, supporting means for the head having a universal joint connection, with said driving mechanism, said supporting means comprising devices for engaging lateral walls of an excavation, 75 and means for shifting said driving mechanism laterally and for changing the angular disposition of the head.

7. In a tunneling and excavating machine, 80 a tunneling head, means for supporting said head, two members for slidably supporting said supporting means one of said members having a universal joint connection with said supporting means, means for holding one member stationary with respect 85 to the walls of the excavation, and means for varying the distance between said members, said supporting means being constrained to move with said movable member, and means for laterally displacing one of said members 90 to effect a change in the angular disposition of the head.

8. In a tunneling and excavating machine, 95 a tunneling head, a supporting member, means for holding said member stationary with respect to the walls of the excavation, a second member, means for shifting the position of said second member with respect to the first member, a driving shaft for said head extending through the members aforesaid and constrained to move with said movable member, one of said members having a universal joint connection with said driving shaft, and means for displacing one of said members to effect a change in the 105 angular disposition of the head with respect to the other of said members.

9. In a tunneling and excavating machine, 110 a tool-carrying head, driving mechanism for said head, means for advancing said head toward the material into which the tools are being driven, said means comprising a plurality of supporting structures, means for displacing one of said structures with respect to another, jacks carried by said structures each comprising a screw-operated, guide-carrying member and a fluid pressure operated part, the fluid pressure operated parts carried by one structure locking said structure against movement, and the 120 screw operated members directing the advance of said structures where not locked.

10. In a tunneling and excavating machine, 125 a plurality of tool-carrying heads, rotatable about a common axis, and an equalizing device co-operating with said heads to equalize the pressure exerted by the tools carried by the respective heads, and means for advancing said heads toward the material to be cut by the tools.

11. In a tunneling and excavating machine, a plurality of tool-carrying heads, rotatable about a common axis, spindles upon which said heads are mounted, a part disposed along said axis, an equalizing device pivotally connected to said spindle and said part and adapted to equalize the pressure exerted by the tools carried by the respective heads, and means for advancing said heads toward the material to be cut by the tools.
12. In a tunneling and excavating machine, a hollow spindle, a rotatable tunneling head carried by said spindle, said head having means for mounting fluid-pressure-operated tools therein, a rotatable support, the respective axes of said head and support being out of alinement, and means for supplying fluid under pressure to said tools comprising a rotatable member, the axis of rotation of which is coincident with that of the support, said member having an aperture therein radiating outwardly from the center portion thereof toward said hollow spindle, said aperture opening into said hollow spindle, and conduits leading from said spindle to said tools.
13. In a tunneling and excavating machine, a tool-carrying tunneling head, mechanism for continuously driving said head, said mechanism comprising means for equalizing the strain upon the tools, and appliances for varying the direction of the cut while continuously operating the machine.
14. In a tunneling and excavating machine, a tool-carrying tunneling head, mechanism for continuously driving said head, said mechanism comprising means for equalizing the strain upon the driving tools, appliances for varying the direction of the cut while continuously operating the machine, and apparatus for removing the muck.
15. In a tunneling and excavating machine, a plurality of rotatable tool-carrying heads, each head carrying a plurality of tools and rotatable about its own axis and about an axis common to all of the heads, and cooperating parts for holding one of said heads in an advanced position and another of said heads in retracted position.
16. In a tunneling and excavating machine, a revoluble support, a rotatable tunneling head eccentrically mounted thereon, means for continuously rotating one of said
- parts and means for differentially driving the other of said parts with respect to the first mentioned part.
17. In a tunneling and excavating machine, a revoluble support, a rotatable tunneling head eccentrically mounted thereon, a planetary drive for operating one of said parts and means for changing the speed of said drive with respect to that of said support.
18. In a tunneling and excavating machine, a revoluble support, a rotatable tunneling head eccentrically mounted thereon, a planetary drive for operating one of said parts and automatic means for changing the speed of said drive with respect to that of said support.
19. In a tunneling and excavating machine, a revoluble support, a rotatable tunneling head eccentrically mounted thereon, a planetary drive for operating one of said parts and means for changing the speed of said drive with respect to that of the support while the machine is in operation.
20. In a tunneling and excavating machine, a revoluble support, a rotatable tunneling head eccentrically mounted thereon, a planetary drive for operating one of said parts, and means for changing the speed of one of said parts with respect to the other while the machine is in operation.
21. In a tunneling and excavating machine, a tool carrying head, driving mechanism for said head, means for advancing said head toward the material into which the tools are being driven, said means comprising a plurality of supporting structures, means for displacing one of said structures with respect to another, jacks carried by each of said structures each comprising an adjustable guide-carrying member and a fluid pressure actuated locking part adapted to engage the wall of the tunnel, the locking parts carried by one structure locking said structure against movement, and the guide-carrying members directing the advance of said structures when not locked.
